UNITED STATES PATENT OFFICE.

MICHAEL McCANANY, OF MILWAUKEE, WISCONSIN.

MEANS FOR SECURING BOOKS TO COVERS.

No. 804,872.

Specification of Letters Patent.

Patented Nov. 21, 1905.

Application filed May 3, 1905. Serial No. 258,585.

To all whom it may concern:

Be it known that I, MICHAEL McCANANY, residing in Milwaukee, in the county of Milwaukee and State of Wisconsin, have invented new and useful Improvements in Means for Securing Books to Covers, of which the following is a description, reference being had to the accompanying drawings, which are a part of this specification.

10 This invention relates to means for securing books to covers, and has for its object to provide an improved device for removably securing a book or pad of any sort to a cover.

15 The invention is applicable to books generally, but is particularly intended for pocket blank-books and card-pads containing a block of blank or printed sheets or of business or visiting cards each adapted to be removed from the book as it is used, said block being

20 removably connected to the cover by a detachable connecting means, so that the block or pad when exhausted may be replaced by another.

25 This invention has for its object to provide such a connecting means for the block and the cover which will be simple in its construction and neat in its appearance, which may be quickly and easily engaged and disengaged, and which may be inexpensive to manufacture.

30 With the above and other objects in view the invention consists in the securing means, its parts and combinations of parts, and all equivalents.

35 Referring to the accompanying drawings, in which like characters of reference indicate the same parts in the several views, Figure 1 is a perspective view of a book and cover provided with the securing means constituting 40 this invention. Fig. 2 is an end elevation of such securing means removed from the book and cover. Fig. 3 is a plan view of the cover member of the securing means. Fig. 4 is an end elevation thereof. Fig. 5 is a longitudinal sectional view of said cover member of

45 the securing means properly attached to the cover. Fig. 6 is a plan view of the block member of the securing means, and Fig. 7 is an end elevation thereof.

50 In the drawings, 8 represents a block or pad of leaves or cards constituting a book, and 9 is the removable cover therefor, to which the end of the book is engaged by the means constituting this invention.

55 The engaging means for the cover and block comprise the cover member 10 and the

block member 11, slidably interfitting with each other, the former rigidly connected to the cover and the latter being rigidly connected to the block. The cover member 10 is 60 preferably formed of a strip of thin sheet metal, with its side edges folded over upon it at its front face and then bent back upon themselves to form oppositely-disposed outwardly-extending engaging flanges 12, with 65 their ends tapered by being cut away obliquely at 13, so that the engaging slide formed by them has its two ends tapering or pointed. On the back of its intermediate portion the main unbent part of the cover member 10 has 70 a pair of tongues 14 struck up therefrom to be embedded in the back of the cover 9, as shown in Fig. 5, and thereby constitute a means for rigidly securing the member 10 to the cover.

75 The block member 11 of the engaging means preferably comprises a strip of thin sheet metal with its side edges bent over upon it to form opposite inwardly-extending engaging flanges 15, so that this member is of a 80 **C** shape in cross-section, as shown in Fig. 7. The ends of the engaging flanges 15 are tapered by being cut away obliquely at 16, so that the slide-groove formed between them has a flaring entrance at each end corresponding 85 with the tapering construction of the ends of the slide of the cover member.

The engaging flanges 12, forming the slide of the cover member, are adapted to hook into and form slip-joints with the engaging flanges 90 15 of the block member. The block of cards or leaves is rigidly mounted on the back of the main or unbent portion of the block member, preferably by having the ends of the leaves glued or cemented thereto. The connection thus constitutes the binding for the block, from which the leaves may be separated one by one as they are used by tearing them loose from the cement which holds them to the block member.

95 In operation the block may be quickly and easily inserted in the cover by passing the slide of the cover member into the slide-groove of the block member, the tapering-end construction of the former and the flaring-entrance construction of the latter facilitating 100 this engagement by guiding the parts to their proper relations. When the block is properly positioned within the cover, it is securely held in place by this connecting means, and 105 the book may be used in the usual manner until the block is exhausted.

When it is desired to replace one block with another or to renew an exhausted block, the old block or the old block member is merely pushed lengthwise off of the cover member, 5 and a new block provided with a block member is slipped thereon, as before. In this way the cover may be refilled as often as desired, and the user is warranted in employing a cover of more expensive material than if the 10 cover were of no further use after its block became exhausted.

What I claim as my invention is—

1. In a device of the character described, a member formed of a strip of sheet metal with 15 its side edges bent over on one face thereof and bent back upon themselves to form oppositely-disposed outwardly-extending engaging flanges, a coöperating member formed of a strip of sheet metal with its side edges bent 20 over on one face thereof to form inwardly-extending engaging flanges to receive between them and form a slip-joint with the engaging flanges of the first-mentioned member, a block 25 of leaves secured on the back of one member, and a cover secured on the back of the other member.

2. In a device of the character described, a member formed of a strip of sheet metal with its side edges bent over on one face thereof 30 and bent back upon themselves to form oppositely-disposed outwardly-extending engaging flanges with obliquely-formed ends, said engaging flanges constituting a slide with a tapering end, a coöperating member formed 35 of a strip of sheet metal with its side edges bent over upon one face thereof to form opposite inwardly-extending engaging flanges with obliquely-formed ends, said engaging flanges of the second-named member producing 40 a groove between them to receive the

slide of the first-mentioned member and form slip-joints with the engaging flanges thereof, the end of said groove being flaring to coöperate with the tapering end of the slide and serve as a means for guiding the slide into 45 the groove, a block of leaves secured on the back of one member, and a cover secured on the back of the other member.

3. In a book, a block of leaves, a cover therefor, and means for securing the block to the cover comprising, a cover member formed 50 of a strip of sheet metal with its side edges bent over on the front face thereof and bent back upon themselves to constitute opposite outwardly-extending engaging flanges with 55 tapering ends, said engaging flanges together constituting a slide with pointed ends, tongues struck up from the main portion of the cover member on the rear face thereof and embedded in the back of the cover, and a block 60 member formed of a strip of sheet metal with its edges bent over on one face thereof to form opposite inwardly-extending engaging flanges with tapering ends, said engaging flanges of the block member forming a groove 65 between them with flaring ends to coöperate with the pointed ends of the slide of the cover member and guide the engaging flanges of the two members into slip-joint relations with each other, said block member having the 70 block of leaves cemented to its other face at the edges of the leaves so that the leaves may be readily removed.

In testimony whereof I affix my signature in presence of two witnesses.

MICHAEL McCANANY.
